CLAIM

The ornamental design for a display panel with animated graphical user interface as shown and described.

DESCRIPTION

1.1 is a front view of a first image in a sequence for a display panel with animated graphical user interface;

1.2 is a second image thereof; and

1.3 is a third image thereof.

The appearance of the transitional image sequentially transitions between the images shown in Reproductions **1.1** to **1.3**. The process or period in which one image transitions to another image forms no part of the claimed design. The dot-dash broken lines define the bounds of the claimed

(Continued)

design and form no part thereof; the evenly-spaced broken lines represent portions of the display panel that form no part of the claimed design.
